UNITED STATES PATENT OFFICE.

WALTER V. TURNER, OF WILKINSBURG, AND JOHN S. CUSTER, OF PITTSBURG, PENNSYLVANIA, ASSIGNORS TO THE WESTINGHOUSE AIR BRAKE COMPANY, OF PITTSBURG, PENNSYLVANIA, A CORPORATION OF PENNSYLVANIA.

FLUID-PRESSURE BRAKE.

No. 810,514.

Specification of Letters Patent.

Patented Jan. 23, 1906.

Application filed April 27, 1904. Serial No. 205,116.

To all whom it may concern:

Be it known that we, WALTER V. TURNER, residing at Wilkinsburg, and JOHN S. CUSTER, residing at Pittsburg, in the county of Allegheny and State of Pennsylvania, citizens of the United States, have invented a certain new and useful Improvement in Fluid-Pressure Brakes, of which the following is a specification.

10 This invention relates in general to automatic fluid-pressure brakes, and has for its principal object to provide means whereby the brake-cylinders of all the cars of a train may be supplied with air at substantially the same degree of pressure regardless of the length of travel of the brake-piston.

With the present standard air-brake apparatus, as is well known, the degree of pressure which will be supplied from the auxiliary reservoir to the brake-cylinder corresponding to any given amount of reduction in train-pipe pressure depends upon the relative capacities or volumes of the auxiliary reservoir and the brake-cylinder; but since the capacity of the 25 brake-cylinder varies according to the travel of its piston a certain length of travel, such as eight inches, has been assumed as standard and the capacity of the auxiliary reservoir made to correspond thereto. Now if the 30 travel of the brake-piston on each car of the train remained constant at this amount—say eight inches—then the pressure in all the brake-cylinders would be substantially the same at each application of the brakes; but

35 it is found in actual practice that owing to various conditions—such as wear of brake-shoes, stretching of brake-rigging, looseness of joints, and careless adjustment—the travel on different cars varies anywhere from four 40 or six inches up to the full stroke of the piston, or twelve inches, and this of course produces corresponding variations in the brake-cylinder pressure from practically zero up to what might be an excessive degree of pressure sufficient to cause a sliding of the wheels 45 of the car. Various slack-adjusting devices for automatically keeping the length of piston travel constant have been proposed, and some of these have been found to operate

50 quite successfully; but these devices have not as yet been generally applied in freight service, to which our invention is particularly applicable.

This feature of our invention comprises a compartment or chamber of a certain predetermined capacity to give the desired pressure corresponding with that of the brake-cylinder at a standard length of piston travel, and combined with this chamber are valve devices operating in response to variations in train-pipe pressure for controlling the supply of air to this chamber at the desired degree of 55 brake-cylinder pressure and means controlled by the pressure in said chamber for regulating the pressure admitted to the brake-cylinder to the same degree. The air for charging this chamber may be taken from the auxiliary reservoir, train-pipe, supplemental reservoir, or other source, and the brake-cylinder may also be supplied from any of these 60 sources or from a combination of any of them.

Another object of our invention is the provision of improved means for maintaining the train-pipe pressure constant while the brakes remain applied and the engineer's brake-valve is in lap position.

In the accompanying drawings, Figure 1 is a diagrammatic view of a standard air-brake equipment with our improvements applied thereto; Fig. 2, a sectional view showing a 65 standard engineer's brake-valve with our improved means for seating the equalizing-piston; Fig. 3, a sectional view of the valve device for maintaining the train-pipe pressure; Fig. 4, a sectional view of a triple-valve device and regulating-valve device constructed in accordance with one form of our improvements, the parts being indicated in release 70 position; Figs. 5 and 6, similar sections of the triple-valve device, showing the parts in service and lap positions, respectively; Fig. 7, a plan view of the valve-seat; Fig. 8, a face view of the main slide-valve; Fig. 9, a face view of the graduating slide-valve; Fig. 10, a diagrammatic view of a car equipment, showing a modified form of our improvement, including a supplemental reservoir; Fig. 11, a sectional view of a triple-valve device and regulating-valve device constructed according to this modification; Figs. 12 and 13, similar sections of the triple-valve device, showing the parts in service and lap positions, respectively; Fig. 14, a plan view of the slide-valve seat; Fig. 15, a face view of the main slide-valve, and Fig. 16 a face view of the graduating slide-valve.

Our improvements are illustrated as applied to a standard air-brake apparatus comprising engineer's brake-valve 1, connected to main reservoir-pipe 2, train-pipe 3, and 5 equalizing-reservoir 4, branch pipe 5, triple-valve device 6, auxiliary reservoir 7, and brake-cylinder 8.

According to the preferred form of our improvement the regulating-chamber of the 10 valve device for regulating the brake-cylinder pressure is charged with air from the train-pipe at the same time that the brake-cylinder is being supplied from the auxiliary reservoir, the triple-valve device being provided with additional ports and passages for 15 performing both functions, as shown more particularly in the figures on Sheet 2 of the drawings, which will now be more fully described.

20 The chamber 43 of the brake-cylinder-regulating device 9 is made of a predetermined capacity, such that the relation between the capacity of the train-pipe of the car and this chamber and the connecting-port is substantially the same as that between the auxiliary reservoir, the brake-cylinder, and the service-port. A valve 46 controls the supply of air from pipe 10 and chamber 47 to chamber 45 and pipe 11, leading to the brake-cylinder 8, 25 30 the valve being operated by the diaphragm 44, which is subject to the opposing fluid-pressures of the regulating-chamber 43 and the brake-cylinder.

The valve-seat of the triple-valve device 6 35 is provided with the following ports: 30, leading to the brake-cylinder; 40, leading to the exhaust; 31, connected to the train-pipe by passage 34; 32, connected to pipe 10, and 33, connected by pipe 12 with the regulating-chamber 43. On the valve-seat is mounted 40 the main slide-valve 28, carrying the graduating slide-valve 29 and operated by the stem 27 of the piston 26 in accordance with variations in train-pipe pressure, the valve-chamber being connected to the auxiliary reservoir in the usual manner. The main valve is 45 provided with service-port 41, emergency-port 42, exhaust-cavity 36, an additional cavity 35, and ports 37 and 38, which are adapted to be connected by cavity 39 in small 50 graduating-valve 29 when in service position, as shown in Fig. 5. In release position of the valve the ports 33, 30, and 40 communicate with the exhaust-cavity 36, so that the 55 brake-cylinder and the chamber 43 are open to the atmosphere, while the auxiliary reservoir is charged from the train-pipe in the usual way. When a reduction in train-pipe pressure is made for a service application of 60 the brakes, the triple piston and valve move back under the preponderating auxiliary-reservoir pressure to service position, as shown in Fig. 5, in which the service-port 41 is open through the main slide-valve and registers with the brake-cylinder port 30, there-

by establishing communication from the auxiliary reservoir to the brake-cylinder. In this position the train-pipe is also put into communication with the pipe 10 through ports 34 31, cavity 35, and port 32, while at the same time the train-pipe communicates with the regulating-chamber 43 through ports 38, cavity 39, ports 37 and 33, and pipe 12. Air then flows from the train-pipe to the regulating-chamber 43 and serves as a local venting of the train-pipe to quicken the action of the triple valves in service applications. At the same time the brake-cylinder is being charged from the auxiliary reservoir through the service-port, and as soon as the auxiliary-reservoir pressure is thereby reduced to or slightly below that of the train-pipe the piston and graduating-valve move to lap position, as shown in Fig. 6.

As before stated, substantially the same regulation exists between the capacities of the train-pipe, the regulating-chamber, and connecting-port as between the capacities of the auxiliary reservoir, the brake-cylinder with standard piston travel, and the service-port, 85 so that the degree of air-pressure admitted to chamber 43 corresponds substantially with that desired in the brake-cylinder for any given reduction in train-pipe pressure. Now if the travel of the brake-piston is accurately 90 adjusted at standard—say eight inches—then the pressure admitted from the auxiliary reservoir to the brake-cylinder will be substantially equal to that which obtains in the regulating-chamber and the regulating-valve 100 will remain closed; but if the brake-piston has a greater travel, which is usually the case, it will be readily seen that owing to the greater volume the brake-cylinder pressure will be less than desired and less than that of 105 the regulating-reservoir. Consequently the diaphragm 44 will be depressed, thereby opening valve 46 and supplying additional air to the brake-cylinder until the pressure therein is equal to that contained in the regulating-chamber, and it will be noted that the triple piston and graduating-valve do not move to lap position until this operation is completed. As this action takes place on 110 each and all cars of the train equipped with this improvement, it will be seen that the 115 brake-cylinder pressure will be substantially uniform throughout the train, thereby securing an efficient and uniform braking power. As the graduating-valve moves to lap position 120 the service-port 41 is closed and communication between ports 38 and 37 cut off, thereby sealing up the air under pressure in the regulating-chamber 43. The train-pipe is still connected with pipe 10, however, 125 through cavity 35 in the main slide-valve, so that should there be any leakage from the brake-cylinder after the triple valve moves to lap position the same would be supplied from the train-pipe by the action of the regulating- 130

valve and diaphragm. In order to maintain the brake-cylinder pressure from the train-pipe in this manner, it is necessary to also provide means for maintaining the train-pipe 5 pressure while the brakes are applied and the engineer's brake-valve is in lap position, and for this purpose the valve device 20 is provided on the locomotive. (See Figs. 1 and 3.) This device comprises a diaphragm 24, sub- 10 ject to the opposing pressures of the train-pipe by pipe connection 22 and the equalizing-reservoir by pipe connection 23, and operates a valve 25 for controlling the supply of air from the main reservoir and pipe 21 to the 15 pipe 22 and the train-pipe. It will now be evident that by means of this device the train-pipe pressure will be maintained from the main reservoir substantially equal to that of the equalizing-reservoir, while the brakes 20 remain applied and the engineer's brake-valve is in lap position.

With the exception of an improvement hereinafter described the engineer's brake-valve, as shown in Fig. 2, may be of the standard Westinghouse type having rotary valve 13, train-pipe passage 14, equalizing-piston 15, and stem 19 for operating the train-pipe-discharge valve. In the standard construction the valve carried by the stem 19 is of the 25 puppet type, and there is no means for positively preventing a slight leakage around the packing-ring of the sliding equalizing-piston. When used with the train-pipe maintaining-valve device 20, connected to the equalizing-reservoir, as shown in Fig. 1, it will be seen 30 that it becomes necessary to prevent the possibility of any leakage from said reservoir around the equalizing-piston to the train-pipe when the brake-valve is in lap position 35 and the train-pipe-discharge valve closed, in order that the pressure on the diaphragm 24 shall remain constant, and according to this 40 feature of our invention means, such as a gasket 16, is provided against which the piston 45 15 may tightly seat when the discharge-valve is closed, and thereby positively prevent any leakage from the equalizing-reservoir. In order to insure the seating of the piston upon the gasket, the train-pipe-discharge valve operated by stem 19 is preferably made in the 50 form of a slide-valve 17, controlling the port 18, and means, such as a light spring 54, may also be used, if desired.

A modified form of apparatus for regulating the brake-cylinder pressure is shown in 55 Figs. 10 to 16 of the drawings, in which a supplemental reservoir 50 is employed. According to this construction the triple-valve device 6' is provided with an additional port 52, connected by pipe 51 with the supplemental reservoir, and the main slide-valve has an additional cavity 53 for establishing communication from the supplemental reservoir to the pipe 10, leading to the regulating- 60 valve when the triple valve is in service posi- 65

tion. When the triple valve is in release position, as shown in Fig. 11, the brake-cylinder and chamber 43 are open to the atmosphere through the exhaust-cavity 36 and port 40, while the supplemental reservoir is charged 70 to normal train-pipe pressure through ports 34 31, cavity 35, port 52, and pipe 51. When a reduction in train-pipe pressure is made for a service application of the brakes, the triple valve moves to service position, as 75 shown in Fig. 12, in which the auxiliary reservoir communicates with the brake-cylinder and the train-pipe communicates with chamber 43, as before described, and the supplemental reservoir communicates with the 80 regulating-valve and pipe 10 through ports 52 and 32 and cavity 53 in the main slide-valve. Air then flows from the train-pipe to chamber 43 and from the auxiliary reservoir to the brake-cylinder, as before described, 85 any additional air required by the brake-cylinder due to excessive piston travel being supplied from the supplemental reservoir through the regulating-valve for bringing the brake-cylinder pressure up to substantially 90 equal that of the regulating-chamber. The triple valve then moves to lap position, as shown in Fig. 13, and any further leakage from the brake-cylinder will be supplied from the supplemental reservoir through the cavity 95 53 in the main slide-valve, pipe 10, and the regulating-valve 47, as will be readily understood. The brakes may be released in the usual manner by increasing the train-pipe pressure. 100

While this improvement is shown as applied to a triple-valve device of the plain type, in which the port 42 is adapted to register with brake-cylinder port 30 in emergency applications, it will be evident the same may 105 also be used in connection with a so-called "quick-action triple-valve device," in which an emergency-valve is used for suddenly venting the train-pipe in emergency applications.

From the foregoing description it will now 110 be apparent that by means of our improvements we secure not only the advantages usually derived from a local venting of the train-pipe in service applications of the brakes, but also the additional and important 115 result of a constant and uniform braking-pressure in all the cylinders, whereby each car is made to perform its share of the work in braking regardless of the length of travel of its brake-piston. 120

The feature of this invention relating to the maintaining of the train-pipe pressure while the brakes are applied, as shown more particularly in Figs. 2 and 3 of the drawings, comprises a very simple and efficient mechanism for accomplishing this result and may be applied to an air-brake apparatus independently of any means for regulating the brake-cylinder pressure. With the present standard apparatus, as is well known, there 125 130

1
is no means for compensating for train-pipe leakage when the brake-valve is in lap position. Consequently after the brakes are applied the train-pipe leakage further reduces 5 the pressure, which causes further graduating movements of the triple valves, thereby applying the brakes harder than was intended and often necessitating a release and reapplication, which wastes a large amount of 10 compressed air. By means of this feature of our invention any leakage from the train-pipe while the brake-valve is in lap position will be replenished from the main reservoir through valve device 20, which is governed

15 by the pressure in the equalizing-reservoir, and the train-pipe pressure will be maintained constant at the given degree of reduction, thereby preventing any undesired further increase in the brake-cylinder pressure.

20 Having now described our invention, what we claim as new, and desire to secure by Letters Patent, is—

1. In a fluid-pressure brake, the combination with a train-pipe, auxiliary reservoir and

25 brake-cylinder, of a regulating-chamber, a valve device for controlling the supply of fluid to said regulating-chamber, and means operated by the pressure in said chamber for supplying fluid directly to the brake-cylinder.

30 2. In a fluid-pressure brake, the combination with a train-pipe, auxiliary reservoir and brake-cylinder, of a regulating-chamber, a valve device operating in response to variations in train-pipe pressure for controlling 35 the supply of fluid to said regulating-chamber, and means operated by the pressure in said chamber for regulating the brake-cylinder pressure.

3. In a fluid-pressure brake, the combination with a train-pipe, auxiliary reservoir and

40 brake-cylinder, of a regulating-chamber, a valve device operated by a reduction in train-pipe pressure for supplying fluid from the auxiliary reservoir to the brake-cylinder

45 and for controlling the supply to said regulating-chamber, and means operated by the pressure in said chamber for regulating the brake-cylinder pressure.

4. In a fluid-pressure brake, the combination with a train-pipe, auxiliary reservoir and

50 brake-cylinder, of a regulating-chamber, a valve device operated by a reduction in train-pipe pressure for supplying fluid from the auxiliary reservoir to the brake-cylinder

55 and for controlling the supply to said regulating-chamber, and a valve device governed by the pressure of said regulating-chamber for also supplying fluid to the brake-cylinder.

5. In a fluid-pressure brake, the combination with a train-pipe, auxiliary reservoir and

60 brake-cylinder, of a regulating-chamber, a valve device operating in response to variations in train-pipe pressure for supplying fluid from the auxiliary reservoir to the

65 brake-cylinder and from the train-pipe to

the regulating-chamber, and means operated by the pressure in said chamber for regulating the brake-cylinder pressure.

6. In a fluid-pressure brake, the combination with a train-pipe, auxiliary reservoir and 75 brake-cylinder, of a regulating-chamber, a valve device operating in response to variations in train-pipe pressure for supplying fluid from the auxiliary reservoir to the brake-cylinder and from the train-pipe to the regulating-chamber, and means operated by the pressure in said chamber for also supplying fluid from the train-pipe to the brake-cylinder.

7. In a fluid-pressure brake, the combination with a train-pipe, auxiliary reservoir and 80 brake-cylinder, of a regulating-chamber of predetermined capacity independent of the brake-cylinder, a valve device operating in response to variations in train-pipe pressure 85 for controlling the supply of fluid to said regulating-chamber, and means operated by the pressure in said chamber for supplying fluid to the brake-cylinder.

8. In a fluid-pressure brake, the combination with a train-pipe, auxiliary reservoir and 90 brake-cylinder, of a regulating-chamber of predetermined capacity independent of the brake-cylinder, a valve device operating in response to variations in train-pipe pressure 95 for controlling the supply of fluid from the auxiliary reservoir to the brake-cylinder and from the train-pipe to the regulating-chamber, and a valve device governed by the pressure of said chamber for supplying fluid to 100 the brake-cylinder.

9. In a fluid-pressure brake, the combination with a train-pipe, auxiliary reservoir and 105 brake-cylinder, of a regulating-chamber, and a triple-valve device comprising a piston subject to the opposing pressures of the train-pipe and auxiliary reservoir, a main slide-valve having ports for establishing communication from the train-pipe to the regulating-chamber, and a graduating-valve for control- 110 ing the ports in the main slide-valve.

10. In a fluid-pressure brake, the combination with a brake-valve having an equalizing-reservoir and a sliding piston for operating a train-pipe-discharge valve, of means for preserving a tight joint around said piston when the discharge-valve is closed and means governed by the pressure of the equalizing-reservoir for supplying fluid to the train-pipe. 115

11. In a fluid-pressure brake, the combination with a brake-valve having an equalizing-reservoir and a sliding piston for operating a train-pipe-discharge valve, a seat adapted to be engaged by said piston when the discharge-valve is closed, and means operated by the 120 opposing pressures of the equalizing-reservoir and train-pipe for controlling the supply of fluid to the train-pipe.

12. In a fluid-pressure brake, the combination with a brake-valve having an equalizing- 130

reservoir, a sliding piston operated by the opposing pressures of the equalizing-reservoir and train-pipe, a slide-valve operated by said piston for controlling a train-pipe-discharge port, a seat adapted to be engaged by said piston, and means governed by the pressure in the equalizing-reservoir for supplying fluid to the train-pipe.

In testimony whereof we have hereunto set our hands.

WALTER V. TURNER.
JOHN S. CUSTER.
